United States Patent Office

Des. 210,774
Patented Apr. 16, 1968

210,774

BASE FOR A TELEPHONE WALL SET

Daniel W. Tyler, Washington Township, Marion County, Ind., assignor to Bell Telephone Laboratories, Incorporated, Berkeley Heights, N.J., a corporation of New York

Filed May 1, 1967, Ser. No. 6,910

Term of patent 14 years

(Cl. D26—14)

FIG. 1

FIG. 2

FIG. 1 is a perspective view of a base for a telephone wall set showing my new design;

FIG. 2 is a side elevation thereof, the opposite side is a mirror image of the side shown.

The telephone handset and cord are shown in broken lines for illustrative purposes only.

I claim:

The ornamental design for a base for a telephone wall set, substantially as shown and described.
